UNITED STATES PATENT OFFICE.

JOSEPH SMITH, OF DENVER, COLORADO.

HOT-AIR FURNACE.

SPECIFICATION forming part of Letters Patent No. 793,617, dated June 27, 1905.

Application filed December 14, 1903. Serial No. 185,145.

To all whom it may concern:

Be it known that I, JOSEPH SMITH, a citizen of the United States of America, residing in the city and county of Denver and State of

5 Colorado, have invented certain new and useful Improvements in Hot-Air Furnaces; and I do declare the following to be a full, clear, and exact description of the invention, such as will enable others skilled in the art to which it
10 appertains to make and use the same, reference being had to the accompanying drawings, and to the letters of reference marked thereon, which form a part of this specification.

15 My invention relates to improvements in hot-air furnaces; and it consists of the features, arrangements, and combinations hereinafter described and claimed, all of which will be fully understood by reference to the accompanying drawings, in which is illustrated an
20 embodiment thereof.

In the drawings, Figure 1 is a vertical section taken through a furnace equipped with my improvements. Fig. 2 is a horizontal section taken on the line 2 2, Fig. 1.

25 The same reference characters indicate the same parts in both views.

Let A designate the fire-box, A' the grate, and A² the ash-pit. The cold air is admitted through a flue B into a chamber C, between 30 the outer casing D and the inner wall E, surrounding the combustion-chamber F. The inner surface of the casing E is provided with a number of hot-air flues G, which communicate with the chamber C by openings G' at 35 their lower ends. These flues G also communicate with the top chamber H by means of openings G² at the tops of the flues. The bottom G³ of each of these flues projects inwardly over the fire-box, and the flues therefore project into the combustion-chamber F, but are entirely separated therefrom. The 40 hot-air flues H' lead from the top chamber H to the various compartments to be heated in the usual manner. A short distance above 45 the openings G' the chamber C is provided with a horizontal partition C', having small orifices C² allowing a small quantity of cold air to enter the chamber C³ above the partition. This chamber C³ communicates with 50 the flues G by means of openings C⁴ at the

top of the flues. The openings C² and C⁴ give increased draft to the hot air and at the same time allow an outlet for the air in the chamber C³.

In the upper part of the combustion-chamber F is located a box I, having a bottom-opening I', adapted to be closed by a damper I², controlled by a rod I³. Communicating also with this box I and extending outwardly therefrom is a number of tubes J, whose outer 55 extremities are located between the flues G. The free extremities of these pipes J are open to receive the smoke and products of combustion from the fire-box. These pipes being located between the upper extremities of the 60 flues G, the heat and products of combustion are compelled to travel practically the entire distance of the flues G on the outside before escaping into the smoke-pipe K, which leads 65 from the box I. 70

In the use of the furnace the damper I' should be left open or thrown to the position shown by dotted lines in Fig. 1 when the fire is first started. This allows the smoke to escape directly from the combustion-chamber 75 to the smoke-flue K, as well as by way of the auxiliary smoke-flues or branch pipes J. When, however, the fire is well started, the damper I' may be closed or thrown to the position shown by full lines in Fig. 1, after which 80 the smoke or products of combustion can only escape from the combustion-chamber by way of the pipes J, compelling them to travel outwardly between the upper extremities of the 85 hot-air flues, thus thoroughly heating said flues and the air passing through them to the compartments to be warmed.

Attention is called to the fact that the inner wall or casing E, together with the flues G, may be formed or molded as an integral casting. The horizontal partition C' may be secured to the said casting by means of screws or bolts, as shown in Fig. 1 of the drawings, the same being passed through a depending flange formed on the partition. 90 95

Having thus described my invention, what I claim is—

1. A hot-air furnace having a casing, a combustion-chamber, a cold-air duct and a smoke-pipe, the casing surrounding the combustion- 100

chamber, and provided with flues which extend inwardly over the fire-box and upwardly through the combustion - chamber, the said flues communicating with the cold-air duct at 5 the bottom and being provided above with an opening for the escape of the hot air, the said flues being cut off from communication with the combustion-chamber, and flues mounted in the upper part of the combustion-chamber 10 and having one extremity in connection with the smoke-pipe, the said flues extending outwardly between the hot-air flues toward the outer wall of the combustion-chamber with which the outer extremities of the flues communicate. 15

2. In a hot-air furnace provided with a combustion - chamber having an outlet for the smoke, the combination with the outer shell of the furnace, of an inner wall or casing surrounding the combustion-chamber the outer shell and inner wall being separated by a suitable space, the inner wall being provided with flues communicating at the bottom with the space between the inner and outer casings and 20 having an outlet at the top for the hot air, the inner wall or casing closing said flues on one side, and the said flues projecting inwardly over the fire - box and extending upwardly through the combustion-chamber, and a number 25 of flues suitably mounted in the upper part of the combustion-chamber adjacent the outlet for the smoke or products of combustion and communicating with the said outlet at one extremity, the said flues projecting outwardly 30 toward the outer wall of the combustion-chamber and communicating therewith at their outer extremities. 35

3. In a hot-air furnace, the combination with inner and outer separated casings forming a chamber, and a cold-air duct communicating with the chamber between said casings, of hot-air flues connected with the inner casing and projecting inwardly into the combustion-chamber and upwardly through said chamber, 40 the inner casing being provided with openings at the bottom leading from the space between the two casings into each hot-air flue, and the latter having a hot-air-escape opening 45 at the top, and a horizontal partition located in the chamber between the two casings and 50 above the openings leading from the said chamber to the hot-air flues, the said partition being provided with small orifices, the upper portion of each hot-air flue being provided 55 with an opening leading from the chamber between the two casings. 55

4. In a hot-air furnace having a fire-box, a combustion - chamber, a cold-air duct and a smoke-pipe, the combination of an inner wall 60 surrounding the fire-box and vertically-disposed hot-air flues extending inwardly from said wall and cast integral therewith whereby the said inner wall closes the said flues on one side, the flues having bottom openings communicating with the cold-air duct and hot-air- 65

escape upper openings, and flues suitably mounted in the upper part of the combustion-chamber and communicating with the smoke-pipe at one extremity and with the combustion-chamber at the opposite extremity. 70

5. In a hot-air furnace provided with a combustion-chamber and smoke-pipe, the combination of an inner wall surrounding the combustion-chamber and having vertically-disposed hot-air flues connected therewith and 75 located in the combustion-chamber, the said flues being provided with cold-air openings at their lower portions and hot-air-escape openings in their upper portions, and branch pipes or auxiliary flues communicating with the smoke-pipe and located in the upper part of the combustion-chamber, the said auxiliary flues projecting outwardly between the hot-air flues and having their free extremities open for the entrance of the smoke and products of combustion. 80

6. In a hot-air furnace, the combination with a smoke-stack of a combustion-chamber provided with vertically-disposed hot-air flues, of a box or receptacle mounted in the upper part 90 of the combustion-chamber and communicating with the smoke-stack, the said box or receptacle being provided with auxiliary open-ended smoke pipes or flues communicating with the said box or receptacle at one extremity, while their outer extremities are located between the hot-air flues in the upper part of the combustion-chamber. 95

7. In a hot-air furnace, the combination with a smoke-stack and a combustion-chamber provided with vertically-disposed hot-air flues, of a box or receptacle mounted in the upper part 100 of the combustion-chamber and communicating with the smoke-stack, the said box or receptacle being provided with auxiliary open-ended smoke pipes or flues communicating with the said box or receptacle at one extremity, the flues extending outwardly from the box toward the outer wall of the combustion-chamber their outer extremities communicating with the combustion-chamber, and a damper connected with the said box whereby 105 direct communication may be made with the combustion-chamber. 110

8. In a hot-air furnace, the combination with 115 a smoke-stack and a combustion-chamber, of a box or receptacle mounted in the upper part of the said chamber and communicating with the smoke-stack, the said box being provided with auxiliary open-ended smoke pipes or flues communicating with the said box at one extremity the flues extending outwardly from the box toward the outer wall of the combustion-chamber their outer extremities communicating with the combustion-chamber. 120

9. In a hot-air furnace, the combination with a smoke-stack and a combustion-chamber provided with vertically-disposed hot-air flues, of a box or receptacle mounted in the upper part 125 of the combustion-chamber and communicat- 130

ing with the smoke-stack, the said box or receptacle being provided with auxiliary open-ended smoke pipes or flues communicating with the said box or receptacle at one extremity, the flues extending outwardly from the box toward the outer wall of the combustion-chamber their outer extremities communicating with the combustion-chamber, a damper connected with the said box whereby direct communication may be made with the

combustion-chamber, and suitable means for controlling the damper from the outside of the furnace.

In testimony whereof I affix my signature in presence of two witnesses.
